RINSING, DRYING, AND CANNING RACK

Sydney N. Ramsdell, Tama, Iowa

Application October 9, 1945, Serial No. 621,297

2 Claims. (Cl. 211—131)

1

This invention relates to a rinsing, drying and canning rack, and more particularly to such a rack for rinsing and drying dishes which may also be utilized for holding jars or cans during a canning operation.

A primary object of the invention is the provision of an improved rack adapted to be rotatably mounted on a support, whereby access may be readily had to any part of the rack.

A further object of the invention is the provision of such a rack which may be readily removed from its associated support when it is desired to utilize the same for canning.

A further object of the invention is the provision of such a rack which, while providing adequate support for dishes or the like, is of open-work construction, in order that air may pass to all parts of the dishes being dried, or water to all parts of the dishes when being rinsed.

A further object of the invention is the provision of a detachable rack in association therewith which may be utilized for holding silverware for rinsing or drying.

Other objects will in part be obvious and in part be pointed out as the description of the invention proceeds and shown in the accompanying drawings wherein there is disclosed a preferred embodiment of this inventive concept.

In the drawings:

Figure 1 is a side elevational view of one form of rack embodying features of the instant inventive concept.

Figure 2 is a top plan view of the device disclosed in Figure 1.

Figure 3 is a sectional view taken substantially along the line 3—3 of Figure 2, certain portions of the mechanism being removed.

Figure 4 is a perspective view of a constructional detail.

Figure 5 is a perspective view of an implement adapted to be utilized in association with the rack.

Similar reference characters refer to similar parts throughout the several views of the drawings.

Having reference now to the drawings, the rack of the instant invention is comprised of a tubular spool 10 open at its lower extremity, and having a plate 11 secured to the top thereof, to which are suitably secured, as by soldering, welding, or the like, a plurality of radial wires 12. The outer extremities of the radial wires 12 are upwardly turned as at 13, and have secured to their uppermost portions a circular wire ring 14. Additional wire rings 15 and 16 are secured to

2

the upright portions 13 at suitable spaced intervals to provide an outer rim for the container.

Circular rings 17 and 18 are also secured to the members 12 at suitable spaced intervals, the rings being of different diameters, to provide a base for the device.

Suitably secured to the outer portions of rings 14, 15 and 16 at diametrically opposed peripheral points are upright portions 20, which extend downwardly substantially to the base of the spool 10, and are then bent at right angles as at 21 and extend inwardly as at 22 to a plate 23 secured to the lower portion of the spool. The members 20 and 22 thus form a supporting frame 15 for the rack comprised of the rings 14, 15 and 16 and the base rings 17 and 18.

A base member is provided for the device, and includes an upright spindle 24 upon which the tubular sleeve 10 is adapted to be placed, and a circular supporting base 25 with which the spindle 24 may be integral, or to which it may be attached.

A rack adapted for the holding of silverware or the like is adapted to be utilized in conjunction with the device and is generally indicated at 26. Rack 26, as best shown in Figure 4, comprises a pair of spaced parallel horizontal rods 27 upwardly turned to form uprights at 28, and terminating in hooked shaped portion 29. Upper horizontal rods 30 extend between the upper extremities of uprights 28 and are secured thereto in any desired manner as by soldering or the like. Spaced U-shaped members 31 are provided along the length of the members 27, and are suitably secured thereto. The upper extremities of the legs of the U-shaped members are secured to the rods 30, while the bases of the U-shaped members extend transversely between the rods 27, thus forming a rack-like structure.

It is pointed out that the legs of the members 31 are materially shorter than the uprights 13, whereby when the device is suspended diametrically across the circular rack above described as by means of the hooks 29 the base thereof is supported a material distance above the base rings 17 and 18. It is to be noted that the ends of the frame are closed by transversely extending rods or bars 32 extending across intermediate points of the uprights 28.

From the foregoing it will now be seen that the device of the instant invention, when supported on the base 25 may be readily utilized for a drying rack for dishes or the like. The dishes obviously will be supported between the rings 17 and 18, and by the radial members 12, and silver-

ware may be readily positioned in the rack 26. By rotating the device any portion thereof may be made immediately accessible to the user in such manner that dishes may be readily placed therein or removed therefrom. The device is preferably of a size to fit conveniently within a sink, and the entire apparatus may be removed from its associated base 25 and positioned in a sink, with the dishes and silverware in position therein for rinsing.

When it is desired to use the device for canning the rack structure may be removed from its base, and the supplemental rack 26 also removed, and a plurality of cans or jars positioned on the circular base rings. The device may then be positioned in a kettle, or the like, for completion of the canning operation.

Under these latter conditions it is desirable to provide means for removing the rack from the kettle in order to obviate the necessity of inserting the fingers in the hot water contained therein. Such means take the form of a member generally indicated at 40 in Figure 5, comprised of two parallel extending legs 41 joined together at their upper extremities as by a transverse portion 42 around which is positioned a heat insulating sleeve 43. The lower extremities of the members 41 terminate in hook-shaped portions 44, which may be readily engaged under the rings 14, two of the members 40 being preferably utilized and engaging the ring 14 at diametrically opposed points. By the use of this device it will be readily seen that the rack may be readily removed from the kettle.

From the foregoing it will now be seen that there is herein provided a device accomplishing all the objects of this invention, and others, including many advantages of great practical utility and commercial importance.

As many embodiments may be made of this inventive concept, and as many modifications may be made of the embodiment hereinbefore shown,

and described, it is to be understood that all matter herein is to be interpreted merely as illustrative and not in a limiting sense.

I claim:

1. In a device of the character described, a hollow tubular spool open on its lower extremity, radial wires secured to the top of said spool and terminating in upright portions, wire rings secured to said upright portions in spaced vertical alignment, wire rings of different diameters secured at diametrically spaced points to said radial wires, and supporting wires having upright portions secured to said first-mentioned rings and horizontally extending portions secured to the lower extremity of said spool.

2. In a device of the character described, a hollow tubular spool open on its lower extremity, radial wires secured to the top of said spool and terminating in upright portions, wire rings secured to said upright portions in spaced vertical alignment, wire rings of different diameters secured at diametrically spaced points to said radial wires, a base including a spindle engageable in said spool, supporting means having upright portions secured to said first-mentioned rings and horizontally extending portions secured to the lower extremity of said spool.

SYDNEY N. RAMSDELL.
